UNITED STATES PATENT OFFICE.

GEORGE N. TSUMURA, OF MOUNTAIN VIEW, CALIFORNIA.

ELECTRICALLY-OPERATIVE CALENDAR DEVICE.

1,190,820.

Specification of Letters Patent.

Patented July 11, 1916.

Application filed May 29, 1915. Serial No. 31,188.

To all whom it may concern:

Be it known that I, GEORGE N. TSUMURA, a subject of Japan, and a resident of Mountain View, in the county of Santa Clara 5 and State of California, have invented a certain new and useful Improvement in Electrically-Operative Calendar Devices, of which the following is a specification.

My invention relates to electrically operative calendar device, and the objects of 10 my invention are, to produce an electrically operative calendar device that can be placed in any desirable location, and operated by an electrical motor, the circuit through 15 which is closed by the minute and hour hands of a clock at midnight, showing the year, month and date of the following day, and one in which said calendar will not operate at the noon hour, when the electric 20 contact is made by the minute and hour hands of a clock.

My invention consists of the parts and combination of parts hereinafter more particularly described and pointed out in the 25 claims.

In the accompanying drawings: Figure 1 is a side elevation of my device, showing the position of shaft bearings, sprocket wheels and sprocket chain, on the outside of the 30 body portion thereof, and spring stop resting on the square end of time shaft inside thereof. Fig. 2 is a side elevation showing the position of gears, trip lever, spring casings, and gear connecting rod, on the 35 outside thereof. Fig. 3 is a detail view of the time shaft and timer thereon, showing tension spring and square end of said shaft, also the four pointed ratchet wheel thereon. Fig. 4 is a detail sectional view on line 40 D—D of Fig. 3. Fig. 5 is a plan view of motor shaft. Fig. 6 is a front elevation of my device with the mechanism in place. Fig. 7 is a sectional view on line A—A of Fig. 6. Fig. 8 is a sectional plan view on 45 line B—B of Fig. 6. Fig. 9 is a front elevation of a clock showing the electric contacts with the hands at 12 o'clock. Fig. 10 is a front view showing the paper calendar drawn down in place at twelve o'clock, mid- 50 night. Fig. 11 is a detail front elevation of cam lever shaft with levers in place. Fig. 12 is a sectional view on line E—E of Fig. 11. Fig. 13 is a front elevation of the cam shaft and connections thereon. Fig. 14 is a 55 detail end view of the cam shaft and connections, parts broken away. Fig. 15 is a

front elevation of the mechanism which revolves the timing shaft. Fig. 16 is a side elevation of Fig. 15.

Referring now to the drawings, in which similar numbers refer to similar parts throughout the several views, 1 is the main body portion of my electrically operative calendar device, the same being made of brass or any other suitable material, and of 60 any size required; 2 is the rods which hold said body portion together by threaded nuts 3, the same being adjustable; 4 is the motor shaft to which is to be attached an electric motor, not shown; the same may be placed 65 in any convenient position, either inside or outside of body portion 1; attached to said shaft shown at 4, on the outside, as shown in Figs. 6—8, near the center of said motor shaft 4, is a pulley 5, adapted to drive 70 governor shaft 69 in connection with pulley 5^a and belt 5^b; attached to the other end of 75 said motor shaft 4, is a driving gear shown at 6; said gear 6 connecting with gear 7 attached to the end of cam shaft 8; near 80 the center of said cam shaft 8 is attached cam 9 and worm gear 10; connected to one end of said shaft 8 between body portion 1 and arm 12, is tension spring 12^c, the same being adapted to take up the lost 85 motion of said shaft 8; inside of body portion 1 is revolving arm 11. On the outside of body portion 1, and revolvably connected to cam shaft 8 by arm 12, and meshing with gear 7, is an intermediate gear 13, said gear 90 13 connecting with gear 14 at predetermined periods, gear 14 being attached to clutch shaft 15 at one end thereof, said shaft passing through sleeve 16 and into sleeve 17, sleeve 16 being movable lengthwise on shaft 95 15; a slot is cut in said sleeve 16, as shown at 18; a pin 19 is fastened to shaft 15 for the purpose of rotating said sleeve 16 with shaft 15. On the inner ends of sleeve 16—17 are fastened the clutch elements 20—21; at 100 one end of sleeve 16 is wound spring 22; this spring is fastened to shaft 15 and to sleeve 16, and is for the purpose of returning said sleeve 16 and clutch 20 to their original position, which will be more fully 105 hereinafter described. On the outer end of sleeve 17 is fastened sprocket wheel 23, to which is connected sprocket chain 24, leading down to sprocket wheel 25, the same being attached to paper roller shaft 26, said 110 shaft having a flat bar 27 fastened to the inner end thereof and projecting a distance

into paper roller 28; at the other end of roller 28 is shaft 29 extending into roller 28 a distance, and held in place by spring 30 and collar 30^b, the same being supported by spring casing 31; said shaft 29 may be drawn back out of roller 28, which permits of easy adjustments of said roller, when required.

Friction roller 32 is shown positioned in body portion 1, the required distance above roller 28, the same being adapted to take up the slack of calendar paper as the same is drawn down by roller 28. Measuring roller 33 is adapted to measure the required distance of calendar paper to be drawn down, and is positioned in body portion 1 the required distance above friction roller 32. Friction roller 34 is positioned in body portion 1, the required distance above measuring roller 33. Feed roller 35 is positioned in body portion 1, the required distance above friction roller 34; feed roller 35 is provided with a shaft bearing 36 at one end thereof, said bearing 36 having a flat bar 37 on the inner end thereof extending into the end of roller 35 a distance; at the other end of said roller 35 is shaft 38, extending into roller 35 a distance, said shaft having a collar 39 thereon, said shaft 38 being held in place by spring 40 and spring casing 41; said spring 40 is for the purpose of adjustment of said roller 35 when required. Measuring roller 33 has spur points extending around the outer surface thereof, as shown at 42, for the purpose of penetrating calendar paper 43, to prevent any slipping of said calendar paper on said measuring roller 33 while in operation; said roller shaft is shown at 33^a; on the outer end of the same is fastened gear 44, meshing with gear 45, said gear 45 being held in place by stud 46, and turnable thereon, said stud being fastened to the outside of body portion 1, in the required position. Attached to gear 45 is trip arm 47; said trip arm 47 at each revolution of said gear 45, comes in contact with trip lever 48 attached to shaft 49; on said shaft is spring 50. At the other end of said shaft 49 is notched bar 51, engaging arm 52, the same being attached to shaft 53; attached to said shaft 53 is clutch engaging arm 54, said arm 54 having a projecting arm 55 attached thereto, said projecting arm 55 engaging with cam 9.

At one end of shaft 53 is shown spring 56; said spring is for the purpose of engaging arm 55 with cam 9, at a predetermined period. On the under side of clutch engaging arm 54 is attached a flat spring 57, said spring having teeth cut in the outer end thereof as shown at 57^a, adapted to engage with worm gear 10 on the underside thereof, when said arm 54 is in its raised position, the same being operated by cam 9.

On one end of shaft 53 is fastened flat spring 58; this spring is for the purpose of operating arms 12 by rod 12^a and cross bar 12^b, connecting intermediate gear 13 with gear 14. Governor shaft 69 has a pulley 5^a attached thereto; the same is driven by motor shaft 4 by the means of a belt 5^b; attached to said shaft is governor 70, the same being weighted at the outer ends of the arms thereof as shown at 71, and pivoted at 72 in the center thereof, said governor being connected to pulley 73 by links 74, said pulley 73 being slidable on shaft 69 by the working of governor 70, said pulley 73 having a spring 75 connected thereto carrying a metal block 76; said block engages arm 77 in notch 78 on the underside thereof when governor 70 is revolving; said arm 77 engages the four pointed ratchet wheel 80, fastened to shaft 81 by notch 79 on the under side thereof, and turns the same quarter way around at each engagement; said arm 77 is operated by spring 77^a, the same being attached to the inner side of body portion 1 and arm 77^b, and by revolving arm 11 attached to cam shaft 8. Said arm 77^b is fastened to arm 77^c by flat spring 77^c, operating around guide 11^a which is of V shape on the inside thereof. The guide 11^a carries arm 77^c out of engagement with revolving arm 11 until motor stops, guide 11^a being pivotally mounted and held in place by brackets 1^a and 1^b, fastened to body portion 1. Fastened to bracket 1^b, is a stop pin 1^c, adapted to engage stop pin 11^e fastened to guide 11^a, which prevents guide 11^a from turning beyond a predetermined point, guide 11^a being operated by spring 11^b; arm 77^c is pivoted to arm 77 by pivot 11^c. Fastened to shaft 81 is timing wheel 82, the same being operated by arm 77; the other end of shaft 81 is made square, as shown at 83, having a spring 84 resting thereon as a tension thereto; timing wheel 82 is made like a propeller wheel for the purpose of engaging and releasing arm 54 at predetermined periods. The electric circuit to electric motor, not shown, is made through the hour and minute hands of a clock at 85—86.

The operation of my device is as follows: When the electric circuit to the motor is made at twelve o'clock, noon, by the hour and minute hands of a clock by contacts 85—86, the motor starts operating governor 70 by belt 5^b, said governor drawing out block 76, the same engaging the outer notch 78 of arm 77, the same being carried over to engagement by arm 11; this prevents the operation of the time shaft until the motor shaft is stopped by the passing of the minute hand of a clock past electric contact 86. The governor then releases block 76, arm 77 is then drawn back by spring 77^a, at the same time turning time shaft 81 one 130

quarter turn around by coming in contact with ratchet wheel 80; this movement partially releases arm 54. At midnight, when the electric circuit to the motor is made, 5 arm 77 is advanced by revolving arm 11 to engagement with ratchet wheel 80 in advance of block 76; arm 77 is then drawn back by spring 77^a, turning time shaft 81 one quarter turn around, releasing arm 54, 10 when said arm is carried over to cam 9 by spring 56; said arm 54 is raised upward by cam 9 connecting gear 13 with gear 14, and arm 54 with clutch 20; by spring 57 engaging with worm gear 10, which connects 15 clutch 20—21, thereby turning sprocket wheel 23 and chain 24, the same turning sprocket wheel 25 and paper roller 28, thus drawing down calendar paper the required distance by measure roller 33 until trip arm 20 47 comes in contact with trip lever 48, when arm 54 drops down, disengaging clutch 20—21 and gear 13, when calendar paper roller 28 stops, leaving calendar paper in place as shown in Fig. 10.

25 Having thus described my invention, what I claim as new and desire to secure by Letters Patent, is:

1. In an electrically operative calendar device, a body portion, means for holding 30 said body portion together, a governor shaft, a motor shaft to which a pulley and driving gear are attached, said pulley being adapted to drive said governor shaft; a cam shaft to which a gear is attached connecting with 35 said driving gear; a cam attached to said shaft, a worm gear attached to said cam and said shaft, a revolving arm attached to said shaft, an intermediate gear connected by arms to said second mentioned gear and 40 operatively connecting with a secondary gear, substantially as shown and described.

2. In an electrically operative calendar device, the combination of a paper roller, and means by which said roller is operated; 45 a friction roller, a measuring roller, and means by which said roller is driven, said roller having spur points on the outer surface thereof; a second friction roller, a paper feed roller, means for adjusting said feed 50 roller, a gear fastened to the outer end of said measuring roller meshing with a gear

carrying a trip arm; a trip lever connecting with said trip arm, a shaft to which said trip lever is attached, a spring on said shaft, a notched bar attached to said shaft adapted 55 to engage an arm, said arm being attached to a shaft; a clutch engaging arm attached to said shaft, a projecting arm attached to said clutch engaging arm adapted to engage with a cam, and means by which said arm is 60 operated, as shown and described.

3. In an electrically operative calendar device, the combination of a shaft to which a cam and worm gear are fastened, a clutch engaging arm, a spring adapted to engage 65 said arm with said clutch, means by which said arm is operated, a revolving arm on said shaft, a timing shaft, and means for operating said shaft; a four pointed ratchet wheel fastened to said shaft, a square end on 70 said shaft, a tension spring resting on said square end, a timing wheel attached to said shaft, means by which said timing wheel is operated, substantially as shown and described. 75

4. In an electrically operative calendar device, the combination of a governor shaft, a governor operative thereon, a metal block operated by said governor, a pulley to which 80 said metal block is connected, links connecting said governor with said metal block, a spring attached to said metal block, a block engaging arm having notches on the underside thereof, a four-pointed ratchet wheel, an arm by which said four-pointed ratchet 85 wheel is operated, a guide by which said arm is carried out of engagement, a revolving arm, a spring by which said arm is operated on its return movement, a timing shaft, a timing wheel, a tension spring resting on the square end of said timing shaft, 90 means by which the electrically operative power is obtained through the hour and minute hands of a clock, substantially as shown and described. 95

In testimony whereof I have hereunto signed my name in presence of two subscribing witnesses.

GEORGE N. TSUMURA.
